UNITED STATES PATENT OFFICE.

JOHN M. BRYANT, OF WEBSTER, KANSAS.

DROPPING ATTACHMENT FOR CORN-PLANTERS.

SPECIFICATION forming part of Letters Patent No. 369,630, dated September 6, 1887.

Application filed March 14, 1887. Serial No. 230,917. (No model.)

To all whom it may concern:

Be it known that I, JOHN M. BRYANT, a citizen of the United States, residing at Webster, in the county of Rooks and State of Kansas, have 5 invented a new and useful Dropping Attachment for Corn-Planters, of which the following is a specification.

My invention relates to improvements in dropping attachments for corn-planters in 10 which crank-shaped levers come alternately in contact with adjustable brackets attached to the spokes of the drive-wheel of the corn-planter, and said levers are so connected and arranged that they move the slide-bar of the 15 droppers alternately to the right and left, as hereinafter described; and the objects of my invention are, first, to provide an automatic dropping attachment worked by the driving-wheel; second, to provide an automatic dropping attachment that can be successfully attached to two-horse corn-planters of any make 20 without changing the construction of the planter; third, to provide an attachment that can be easily and quickly thrown out of gear, so that it will not drop or operate while being transported from field to field. I attain these 25 objects by means of the mechanism illustrated in the accompanying drawing, in which the figure is a partial rear view of the attachment as it appears secured to a common two-horse corn-planter.

The attachment is fastened to the right-hand drive-wheel and seed-box and to the slide-bar of the planter.

35 In the drawing all of the parts excepting the drive-wheel, seed-box, and slide-bar are omitted, as they are considered unnecessary to an understanding of the workings of my invention.

40 4 is the slide-bar of the planter, and is moved alternately to the left and right by means of the pitman 5, which is connected with the crank-lever 6 by means of the lever-arm 7, which is rigidly attached to crank-lever 6.

45 8 is another crank-lever, which works alternately with lever 6 and directly opposed to it, and the two crank-levers 6 and 8 are connected by means of the pitman 9, which is attached to the arms 10 and 11, which are rigidly attached to levers 6 and 8, respectively, as illustrated in the accompanying drawing.

50 The two crank-levers 6 and 8 are supported

in position and work in bearings in the clamp 55 a, which clamp is itself attached to the seed-box 3 by means of bolts b b passing through the clamp a a near the ends of its jaws. By tightening the bolts b b the pressure of the clamp-jaws a a becomes so great that they are held permanently to the sides of the seed-box.

The crank-levers 6 and 8 are worked by having their crank-arms c and d forced downward 60 by contact with the brackets f and g, respectively, which are attached to the spokes of the drive-wheel 2 by means of staple-shaped bolts and clamp-plates. Thus, as shown in the drawing, the bracket f is attached to project 65 on the left side of the spokes of the drive-wheel, and is about to engage crank-arm c, which will force it down, thus forcing the arm 7 to the left, carrying with it pitman 5 and slide-bar 4, and also forcing arm 10, pitman 70 9, and arm 11 to the right, thus raising the end of crank-arm d into position to engage with bracket g, which is attached by means of staple-shaped bolts and clamp-plates to project 75 from the right-hand side of the spokes and on the opposite side of the wheel and hub from bracket f. When bracket g engages with crank-arm d, it forces it down and to the right, and by the connection moves the slide-bar 4 to the right, and raises the end of crank-arm 80 c to proper position to engage again bracket f alternately. The pitman 9 has each end bent to a right angle with the shaft of the pitman, and the bent ends pass through corresponding holes in the lever-arms 10 and 11, thus connecting them.

To throw the attachment out of gear, it is only necessary to disconnect the lever-arms 10 and 11 by detaching one end of the pitman 9, thus allowing the ends of the crank-arms c and 90 d to remain down and out of reach of the brackets f and g.

The lever-arms 7, 10, and 11 are welded to their respective crank-levers 6 and 8, and work with them. The lever-arm 7 may be provided 95 with holes at different distances from its lower end, by means of which the pitman 5 may be attached by a bolt, so that it can be adjusted to make a longer or shorter stroke, as may be desired.

The brackets f and g may be adjusted to project more or less, as the case demands, by slid-

ing the arms of the brackets between the clamp-plates and the spokes of the wheel, as shown in the drawing.

I claim as my invention and desire to secure
5 Letters Patent for—

1. In a corn-dropping attachment for planters, the crank-lever 8, provided with arms *d* and 11, and crank-lever 6, provided with arms *c*, 10, and 7, and pitman 9, in combination with
10 cam-brackets *f* and *g*, secured to the spokes of the covering-wheels, all substantially as shown and described.

2. In a corn-dropping attachment for planters, the seed-box or hopper 3, secured in position by means of bolts *b b*, the clamp-bars *a a*, 15 on which are journaled crank-levers 8 and 6, provided with arms *d* and 11, and arms *c*, 10, and 7, respectively, and pitman 5, connected to the seed or slide bar 4, all substantially as described.

JOHN M. BRYANT.
